UNITED STATES PATENT OFFICE.

GEORGE RODNEY MOORE, OF LYONS, IOWA.

IMPROVED STOVE-PIPE CONNECTION.

Specification forming part of Letters Patent No. 44,440, dated September 27, 1864.

To all whom it may concern:

Be it known that I, GEORGE RODNEY MOORE, of the city of Lyons, in the county of Clinton and State of Iowa, have invented a new and useful Improvement in the Mode of Connecting Pipe with Stoves and Heaters; and I do hereby declare the following is a full and exact description thereof, reference being had to the accompanying drawings, and to the letters of reference marked thereon.

The Figure 1 is a perspective view of a plain cylinder stove with my invention shown in the usual place of the smoke-pipe.

A is a direct flue from the stove with which the pipe is to be connected. Its end is cut obliquely at or about an angle of forty-five degrees.

B and C constitute one piece, which is cast separately from A. The outline of B forms a right-angle triangle and its hypotenuse matches A.

G is the proper flange to receive the smoke-pipe.

A and B are held firmly together by a rod or bolt, a, and the burr b. By unscrewing b upon the bolt a, B will be loosened in its junction with A and can then be turned so as to bring C into a direct line, as seen in Fig. 2. Thus easily is the pipe placed in either a horizontal or a perpendicular position, as the operator may wish. It is obvious the manufacturer may give these parts any shape he may wish, only so that the parts A and B will match when turned either way—*i. e.*, to accommodate either a perpendicular or a horizontal pipe.

Having thus fully described my invention, what I claim therein as new, and desire to secure by Letters Patent, is—

The reversible connection of B and C with A, substantially in the manner and for the purposes herein set forth.

GEO. R. MOORE.
